Application December 19, 1935, Serial No. 55,170
In Germany December 24, 1934

8 Claims. (Cl. 270—79)

This invention relates to a process for measuring the lengths of single or double running webs in folding machines having pressure grippers.

In the known folding machines there will occur, when folding the web by folding blades or the like, a certain tension of the web. If the web is released by lifting the pressure grippers or catchers known per se with folding machines a slackening of the laid fold and thus a shortening of the fold length in relation to the adjusted hub of the folding shovel will take place. For this reason it was necessary heretofore to rely on individual discretion and judgment in extending the hub of the folding shovel to a length greater than that theoretically required for a given measurement. As different webs necessarily possess different possibilities of tension it has been necessary to adjust the hub of the folding shovel by hand for each different web and consequently a gaugelike measuring of the web in a folding machine was not possible.

According to the present invention the difference between the laid slackened fold length and the theoretical length of a slackened fold is made use of for adjusting and regulating the length of the fold to be newly laid.

This is accomplished by letting a groper feel along the folded edge of the topmost slackened fold and by regulating the hub length of the folding shovel for the top fold according to the position of said groper.

If, because of the slackening of the web, there is found in the topmost laid slackened fold a variation from the proper measurement, the new top fold being formed will, by changing the hub length of the folding shovel, be changed to correct said variation so that in the new topmost fold the fold length will approach the desired measurement.

Since webs of different thickness are measured in the folding machine, there may occur at the reversing point of the laid fold, due to the thickness of the web itself, a wrong adjustment in respect to the desired length of fold. In order to avoid this disadvantage the feeling or groping levers with their appliances are adjusted in relation to the desired measurement, taking into consideration the actual thickness of the web. This adjustment can take place either by hand or automatically.

In order to avoid the mistake which on feeding along the pile might occur through the change of level of the top layer, the table for receiving the pile will be automatically lowered in a manner known per se in accordance with the changing

level of the pile, so that the feeling or groping levers will always come into contact with the fold formed at the same horizontal level.

Instead of the automatic mechanical lowering of the table as just described, the lowering may be effected by having the table mounted more or less resiliently, as on springs, so that it will be lowered by the increasing weight of the material folded thereon together with the downward pressure of the holding grippers. In this case the upward pressure supporting the table should be slightly more than the downward pressure of the material, but slightly less than the combined downward pressure of the material and the grippers.

It may be noted that folding machines and web tensioning machines heretofore known had employed gropers or the like to regulate the web supply by feeling along the longitudinal edges of the incoming web, as distinguished from applicant's arrangement in which the gropers contact the folded edges of the web.

Constructions are also known in which the hub of the knife in web folding machines is displaced by mechanical means; but it must be noted that in such prior constructions the displacement of the knife is not adjustable to correspond with the difference in length between the laid fold of the material and the measurement which is desired.

A practical embodiment of the invention is represented in the drawings in which

Figs. 1 and 2 represent diagrammatically in longitudinal vertical section a folding machine, showing respectively two different positions of the folding blade or shovel;

Fig. 3 shows the pressure grippers in a plan view;

Fig. 4 shows diagrammatically the device for automatically regulating the feeling and groping levers for running webs of different thickness;

Figs. 5 and 6 show two different constructions for automatically adjusting the table downwards in correspondence with the level of the pile;

Fig. 7 shows diagrammatically the apparatus for regulation of the folds; and

Fig. 8 shows diagrammatically a modified form of the folding machine.

Figs. 1 and 2 refer to a folding machine of a known type, in which 1 is the crank shaft driven for instance by a motor. The crank 2 mounted on the shaft moves a crank rod 3 one end of which is formed as a rack arranged to engage the pinion or gear wheel 5 fixed on the shaft 4. By this means the shaft 4, together with the

driving pulley 6 also fixed thereon, will be periodically turned towards left and right during each rotation of the crank shaft 1. This periodical movement is transferred to the steel band or belt 9, passing around the pulley 6 and guide rolls 7 and 8, the steel band having inserted therein a pair of reversing blades 10, 10, mounted on a horizontally guided carriage 11.

The latter will consequently receive a periodical to and fro movement in a horizontal direction; at the same time in a known manner the pair of reversing blades 10, 10 is turned around the horizontal pivot 12 mounted in the carriage 11 by means of a turner 14, pivotally mounted at 15 13 and changing its angular position.

The web 15 is pulled down by means of a folding shovel together with the reversing blades 10, 10 over the guiding rollers 16, 16, and when using doubled webs over the doubling rods 17, 17, from 20 the doubling angle 18, and is, in a known manner, put by the pressure grippers 19 and 20 onto the table 21 in layers to form a pile, the fold length of which is to be a measured unit, for instance one meter.

25 In order to be able according to the present invention to alter the hub of the folding shovel, the axle 13 of the governing arm 14 carrying the folding shovel is connected with the worm 26 by means of a lever 25, pivoting around the bolt or pin, and by means of the worm wheel segment 24. This worm 26 is fixed to the shaft driven by the motor 27 and is arranged preferably to be self-retarding in action.

The governing of the motor 27 in this case 35 takes place by means of the feeling or groping lever 31, which comes to lie against the edge of the fold and which is passed through an opening 29 in the pressure gripper 20. In order to ensure, when beginning to lay the pile, that the 40 feeling or groping lever will come to lie against the edge of the first fold, the table 21 for receiving the pile is provided with an opening 30. The feeling lever 31 is provided at its rearward prolongation with a contact 32, swinging between the contact springs 33, 34, the latter being connected by conducting wires with the motor clamps 35, 36, corresponding to the forward or backward running of the motor 27.

The contact 32 is connected by means of a 50 movable small cable with the clamp 37, from which, as from the third motor clamp 38, conducting wires 39, 40 run to the electric source.

Inserted into one of these conducting wires, for instance 40, there is a pair of contacts 41, 42, 55 periodically actuated to permit the passage of the current only when the top web layer is in a slackened state. For this purpose there is arranged on the main shaft 1 of the folding machine a cam disc 43 having a notch 44, into which 60 the roller 45 on the lever 47 pivotally mounted at 46 and carrying the contact 41 can fall, thus closing the circuit between contacts 41, 42 and effecting the connection of the governing device with the electric source.

65 This is arranged to take place when the top web layers of the pile are in a slackened condition. Such working position is shown in Fig. 2. The reversing blade 10, 10 has, after feeding the web to the pressure gripper 19 shown on the left side, again returned with the fold and will only be a few centimeters in front of the pressure gripper 20 (on the right side), which is lifted (by means of known devices not shown in detail) at the same time releasing the top layer, still under 70 tension up to then, and permitting the same to

assume the normal length corresponding to its slackened condition. At this moment the feeling action of the groping lever 31 will become effective, because at the same time the roller 45 drops into the notch 44 on the cam disc 43 permitting the lever 47 to drop, so as to close the pair of contacts 41, 42 and complete the connection with the electric source along the conducting wire 40.

Now if the contact 32 of the groping lever 31 touches one of the two contact springs 33, 34, an operating current will pass through the motor winding arranged for right hand or left hand revolution, and the pivoting point 13 of the reversing device 14 will accordingly be lifted or 15 lowered, until the current is turned off by separating the contacts 41, 42, which occurs as soon as the cam disc 43 rotates sufficiently to raise the roller 45 on lever 47 out of the notch 44.

The interruption of the contacts 41, 42 must 20 take place before the formation of the top web fold is completed, because otherwise the latter would, owing to the increased hub length of the folding shovel, protrude and disturb the correct regulation.

25 The entire groper device 48 containing the contact pieces 32-34 and the groping lever 31 can be mounted on the frame of the machine and adjusted by a handle 49 at the marked point 50, for a given unit of measurement such as: 30 fold length—one meter.

If webs of different thickness are to be measured, the influence of the changing thickness of the web can be compensated for either by correspondingly adjusting the groper device itself 35 or by adjusting the countercontacts coacting with the groper. For adjustment by hand, the groper device is slidably arranged on a support or rail and is moved along the rail, in accordance with the thickness of the web, in such a 40 manner that the groper will come to lie against the topmost slackened fold.

This adjustment can also take place automatically, and Fig. 4 shows such mode of construction for an automatic regulation and adjustment of 45 the contacts, co-acting with the groper. There is arranged a groping device 52 having a two armed lever 54 turnable around an axis 53, which lever carries the countercontacts 55, 56.

The lever 54 with the countercontacts 55, 56 50 is rocked by the pushing rod 58 guided at 57 and being under tension of a spring 61, the pushing rod having mounted thereon a roller 59 bearing against the web 15, at a point where it is supported by a second roller 60 mounted on a fixed 55 axle and acting as a counterbearing.

In order to ensure that the gropers 31, 32 properly feel along the top web layer of the pile 22, it is essential that said layer will always remain at approximately the same level. For some webs 60 the regulation by the pressure of the pressure grippers will suffice, whereas for other webs it will be necessary to provide a device for lowering the table having automatic height adjusting means, such as are known with other textile machines, for instance with machines for inserting pressboards into cloths or webs.

65 Two such governing devices operating on different principles are shown in Figs. 5 and 6.

70 Fig. 5 shows the web pile 22 reposing on the table 21, the pressure grippers 19 and 20 being under the tension of the springs 88, 89 resting on the top fold of said pile. The position of the grippers may thus be taken as a measure for the 75

level of the top web layer and used for interpolating a governing electric current.

For this purpose the levers 90, 90' carrying the pressure grippers 19, 20 have two arms and bear 5 the contacts 92, 92', being connected to the conducting line 91, which contacts will, when the top web layer is on a correct level, come to lie just in front of the respective countercontacts 93, 93'. The contacts 92, 92' and 93, 93' are 10 connected in parallel and there leads from the contacts 93, 93' a further conducting line to the clamps 95 of the motor 94, whereas there is connected to the other motor clamp 96 the conducting line 97, which runs back to the electric 15 source.

If the pile 92 exceeds the normal level the pressure grippers 19, 20 will be lifted, the levers 90, 90' will be turned and the contacts 92, 92' will be brought in touch with the countercontacts 93, 93', thus closing the circuit which operates the motor 94. The latter begins to turn and drives the rack 103 by way of the worm 98 coupled to the motor, the worm wheel 99, the pair of gear wheels 100, 101 and the pinion 102, so 25 that the table 21 connected to the rack will be lowered together with the pile 22. This takes place until the contacts 92, 93 and 92', 93' again open and the motor 94 is again stopped. This operation will be repeated from time to time on 30 any further rising of the level of the pile.

In order to inhibit said regulation during the working positions, in which the pressure grippers 19, 20 are lifted from the pile 22, the electric current will be interrupted during this time by a 35 pair of contacts 108, 109, interpolated into the conducting line 91. For this purpose a cam disc 104 having two noses 105, 105' is mounted on the main shaft 106, which disc periodically lifts the roll lever 107 together with the contact 108 connected thereto and thus breaks the contact at 108, 109. In order to allow the levers 90, 90' to swing out on lifting the pressure grippers 19, 20, the contacts 93, 93' are fastened to levers 111, 111', which are resiliently held in operative 40 position against the adjustable stops 112, 113 by means of springs 110, 110'.

Fig. 6 shows another solution of the problem in which the drive for lowering the table is not effected by the governing motor but by the shaft 50 of the machine, the reversible motor serving only to regulate the rapidity of lowering.

For this purpose there is arranged on the lever 90 serving for moving the pressure gripper 20 a contact 113 having two contact surfaces, which 55 contact moves between the contacts 93 and 114. The contact 93 is again fastened on the lever 111 held by the spring 110 against the screw 112, whereas the contact 114 is stationary but adjustable. Each contact is connected by conducting lines with the motor clamps 115 or 116 respectively for causing forward or backward operation of the motor 119 whereas the third motor clamp 117 is connected to one of the conducting lines 119, the other conducting line 120 being connected to the governing contact 113.

The lowering of the table is effected by the main shaft 121 of the machine, which by an eccentric 122 seated on the same imparts to the pawl 124 an oscillating movement with the assistance of a pushing rod 123, so that the ratchet wheel 125 is turned and effects with the aid of the pinion wheel 126 and the rack 127 the lowering of the table 21 together with the pile 22.

The number of teeth of the wheel 125 interpolated on each oscillation may be regulated by ad-

justing the trip cam 129 fixed to the lever 128, which cam will coat with the roll 130 on the back of the pawl 124 and lift the pawl 124 from the teeth of the wheel 125. The lever 128 pivotally mounted on the shaft 131 of the wheel 125 carries 5 a worm wheel segment 132, which coats with the worm 133 coupled with the motor 118.

When the level of the top fold changes, the contact 93 or 114 will be closed upon the contact 113 and the motor 118 is switched in for a forward or 10 backward run, so as to provide a proper regulation of the distance between the cam 129 and the roll 130 and thus of the number of teeth of the wheel 125 moved at each oscillation.

With this gearing also there is provided a roll 15 lever 134 which is lifted by a nose 135 of the cam disc 136 and effects the separation of the pair of contacts 93, 114 interpolated into the conducting line 120 as soon as the pressure gripper 20 is lifted 20 during the work.

With the above described mode of construction the amplitude of the groper in correspondence with its deviation from the desired position of measurement is made use of for regulating the hub length of the folding shovel for the first layer 25 of the topmost fold when the latter is formed. For this adjustment there is only given a comparatively short time which may cause difficulties in effectively regulating the hub length of the folding shovel. 30

In order to avoid this disadvantage and to obtain more time for the adjustment of the hub length of the folding shovel, the construction shown in Fig. 7 may be used, in which the amplitude of the groper, in accordance with its deviation from the desired position of measurement 35 serves to regulate the hub length of the folding shovel for the second layer of the fold being newly formed above the fold already felt along by the groper, or for one of the layers of the folds immediately following the same, in which case the folds already regulated in their length are used with the intermediate of the groper for regulating the hub length of the folding shovel. 40

As will be seen by the diagrammatic drawing 45 Fig. 7, A is a slackened fold already regulated in its length, against the edge *a* of which the groper *c* comes to lie. The groper, as in the mode of construction shown in Figs. 1 to 6, operates in connection with the device for regulating or 50 adjusting the hub length of the folding shovel.

However, with the mode of construction shown in Fig. 7 the play of the groper *c* is not made use of for the first layer *d* of the fold *B* to be newly laid, but for regulating the length of the second 55 layer *e*. In order to form the fold *B*, newly to be laid, naturally the pressure gripper 20 according to Fig. 8 must come to lie on the fold *B* newly formed, so that the length of said fold lying immediately beneath the pressure gripper can on 60 this side not be adjustably regulated.

The adjusted hub length of the folding shovel for the second layer *e* will still have its effect also on the next fold *C* consisting of two layers, and as a regulation command is not given by the edge of, 65 the fold *B*, this adjustment of the hub length will also have its effect on the fold *D*.

Since, however, in the meantime the groper *c* has felt along the edges of the layer *C*, a regulation command will again be given and a regulation of the hub length of the blade will then take 70 place with the second layer of the fold *D*.

A feeling along the edge of the fold *B* will not take place because this edge has not as yet been correctly regulated by the groper. If also the 75

edge of the fold B were to be felt along by the groper and a regulation command be given, an over-regulation would take place which would act disadvantageously.

5 The groper will thus, whilst skipping one fold, always feel along the edge of the next fold but one, viz: the folds already regulated in their length are utilized by the groper to regulate the hub length of the folding shovel. The interruption 10 of the action of the groper c will take place by means of a periodical switch known per se; which interrupts the electric current within the groper c in accordance with the position of the cam disc 137, such as has been explicitly described 15 for the construction according to Figs. 1 to 6. As the roll 138 feels along the periphery of the disc 137, the points of contact 139, 139' are separated and the current will not be able to flow within the conducting wires 140 to the groper c. However, when the roll 138 falls into the groove 141 20 of the disc 137 the circuit is closed at 139, 139'; and the position of the disc 137 with its groove 141 is so selected that the flow of current will only take place at the moment when the pressure 25 gripper 20 presses onto the web and the groper c is in the neighbourhood of the fold edge to be regulated.

In order to adjust the play of the groper c 30 in accordance with the fold edge to be felt along, and in accordance with the desired fold length regulation (by changing the hub length of the folding shovel), the groove 141 of the disc 137 can be made correspondingly long, so that the 35 time for regulating the hub length of the folding shovel by the groper c can be prolonged at will.

The process according to the invention as shown 30 in the diagrammatic drawing Fig. 7, is as follows:

According to the scheme shown the slackened 40 fold A is shown in a full line; the fold B is also shown in a full line, but in the second layer e a part beginning at line f is drawn in a dotted line, which is to show the beginning of regulation 45 of the hub length. The fold C is drawn in a dotted line, to show that the regulated hub length also has its effect on said fold C. Also the fold D is drawn in a dotted line to show that the hub regulation will partly also extend to this fold. With the fold D the fold edge D' shows the position 50 of the fold in a tensioned state, and after de-tension or slackening the fold D' will go back to D''. The second layer of the fold D is drawn on from the point g in dot and dash manner, which again is to show that the hub regulation of the folding shovel begins.

55 It will be understood that various changes may be resorted to in the form, material, construction, and arrangement of the several parts, without departing from the spirit and scope of my invention; hence I do not intend to be limited to the 60 details herein set forth except as they may be included in the claims.

What I claim is:

1. The process of measuring and determining the length of fold in a web folding machine having pressure-grippers which includes, feeling along the folded edge of the topmost slackened 5 fold to ascertain the actual position of said edge and regulating the length of a succeeding fold in accordance with the deviation of said actual position of the folded edge from the desired position thereof.

2. The process of measuring and determining the length of fold in a web folding machine having pressure-grippers which includes, feeling along the folded edge of the topmost slackened 15 fold to ascertain the actual position of said edge and regulating the extent of effective folding motion of the folding mechanism in accordance with the deviation of said actual position of the folded edge from the desired position thereof.

3. A web folding machine, comprising a pivoted 20 reciprocating folding shovel, a groping device adapted to bear against a folded edge of the material, means for adjusting and regulating the hub length of the folding shovel and means for controlling said adjusting and regulating means 25 in accordance with the position of the groping device.

4. A web folding machine, comprising a pivoted reciprocating folding shovel, a groping device adapted to bear against a folded edge of the material, means for adjusting and regulating the hub length of the folding shovel and electrical 30 means for controlling said adjusting and regulating means in accordance with the position of the groping device.

5. A web folding machine according to claim 4 35 including means for rendering inoperative the electrical means for controlling said adjusting and regulating means during part of the cycle of operation of the machine when the groping device 40 is not bearing against the edge of a fold.

6. A web folding machine according to claim 3 comprising an adjustable support for the groping device, whereby the position of said device 45 may be changed in accordance with the thickness 45 of the web to be measured.

7. A web molding machine according to claim 4, comprising contact surfaces disposed on each side of the groping device and means for moving 50 said contact surfaces, said means including a fixed roller adjacent one surface of the web to be folded, a movable roller adjacent the opposite surface of the web and a connection between the movable roller and the contact surfaces.

8. A web folding machine according to claim 3 55 comprising a movable table for receiving the pile of folded material and automatic means for adjusting the height of said table with respect to the position of the folded edge acted on by the groping device.

JOHANNES MENSCHNER.
